PORTABLE AUTOMOBILE WARNING AND UTILITY LIGHT

Albert G. Busch, Des Plaines, and Joseph W. Focosi,
Chicago, Ill.

Application January 17, 1955, Serial No. 34,005

Term of patent 14 years

(Cl. D48—20)

FIG. 2

The dominant features of my new design are shown in solid lines.

We claim:

The ornamental design for a portable automobile warning and utility light, as shown and described.
